UNITED STATES PATENT OFFICE.

HENRY SKELTON, OF CABERY, ILLINOIS.

CULTIVATOR.

SPECIFICATION forming part of Letters Patent No. 334,479, dated January 19, 1886.

Application filed November 2, 1885. Serial No. 181,631. (No model.)

To all whom it may concern:

Be it known that I, HENRY SKELTON, a citizen of the United States of America, residing at Cabery, in the county of Ford and State of Illinois, have invented certain new and useful Improvements in Cultivators, of which the following is a specification, reference being had therein to the accompanying drawings.

Figure 1 is a side elevation of the cultivator as it appears when equipped for riding. Fig. 2 is a top plan view of the same. Fig. 3 is a cross-section of the cultivator immediately in front of the axle, looking toward the axle, and having the traveling wheels removed. Fig. 4 is a view of the rear portion of one of the beams, showing a handle attached thereto, as used when the cultivator is equipped for a walking-cultivator. Fig. 5 is a side view of a portion of the evener and its supporting stand and a cross-section of the tongue and a portion of the plates below said tongue, showing the manner of attaching said parts to the tongue. Fig. 6 is a side view of one of the beams having a set of shovels and their standards secured thereto. Fig. 7 is a top plan view of the rear end of the same. Fig. 8 is a side view of a set of shovels and their standards disconnected from their supporting-beam. Fig. 9 is a perspective view of a shovel. Fig. 10 is a top plan view of the adjustable plates, which are secured to the under side of the tongue and to which the shovel-beams are attached through the medium of angular plates; and Fig. 11 is a perspective view of the angular plate for adjustably securing the shovel-beams to the adjustable plates, which are in turn secured to the under side of the tongue.

This invention relates to certain improvements in two-wheeled cultivators, which improvements are fully set forth and explained in the following specification and claims, reference being had to the accompanying drawings making a part of this specification.

Referring to the drawings, and looking more particularly at Figs. 1, 2, and 3, A represents the axle of the cultivator having axle-shanks A' at each end, upon which are ordinary axle-spindles upon which are placed the traveling wheels W W. The axle-shanks A' support the axle high enough, so it may be above the working parts and high enough to clear a row of corn.

T represents the tongue, having the rear end secured to the center of the axle and provided with a pair of braces extending from the outer ends of the axle to about where the evener is attached, which tongue-braces and axle constitute the frame proper. The tongue T is slotted from near its rear end to a point a little in advance of the evener E, as shown in Fig. 2.

To the under side of tongue T is adjustably secured a circular plate, J, by means of bolts c and c' passing up through slot T' of the tongue. To the under side of said plate J is pivotally secured another plate, O, by means of a bolt, c'', passing up through plate J and said slot T', which plates and their said manner of attachment are shown in Figs. 2, 5, and 10. The plate J is provided with a pair of opposite concentric slots, a''. (See Fig. 10.) The plate O is provided with a pair of holes immediately under said slots of plate J for the reception of bolts a'', which bolts are for the purpose of clamping said plates together and holding them clamped together in any position desired within the limit of said slots, and for more thoroughly supporting said plate O. Said plate O is also provided with the perforations d'' and slots d'', for the purpose of the attachment to said plate of the angular plates F, such as shown in Fig. 11, which angular plates are provided with the perforations d' and d'', and slots R' and Q'. Angular plates F are attached to plate O, one on either side, as shown in Fig. 2, by means of the bolts d d, passing through perforations d' of plate F and d'' of plate O, which pivotally connect plates F with plate O. Bolts Q pass through the slots Q' of plates F, and slots d'' of plates O, to adjustably secure the plates together at that place.

B represents the beams, one of which is shown in detail in Fig. 6, having a slot, c'', through its front end, and a bolt-hole, c'', a short distance back from the front end, and the said beams are attached at their front end to the vertical sides of angular plates F by means of a bolt, c'', passed through the slot in the front end of the beam and the perforations d'' of said plate, and a bolt, c'', passed through bolt-hole c'' of the beams and slot R' of said plate, as shown in Fig. 1. These bolts are left loose enough, so the beams may have free movement on said

plates, and so the rear end of the beams may be elevated and the beams moved forward, so the bolt c^2 in slot R' may be hooked into the notch R^2 at the upper end of said slot to hold the rear end of the beams elevated, so the shovels will not engage the earth, when desired. The elevation of the beams is accomplished by means of a pair of treadles, G , through the medium of chains d' , which connect said treadles with said beams. These chains pass over the pulleys M , secured to the front side of the axle, and attach to the treadles by means of hooks and to the beams through the medium of loops e on the inner sides of the beams, as shown in Fig. 3. To the rear ends of the beams are attached the angular plates P , as shown in Figs. 6 and 7. The horizontal parts of these plates are provided with the slots P' at their front ends and a bolt-hole at their rear ends. The rear ends of the beams are also provided with corresponding bolt-holes, and the said plates are pivotally secured to the under side of the beams by means of the bolt J' , as shown in Fig. 7, and adjustably held thereto by means of the bolts J^2 , passing through the beam and the slot P' of said plate, as shown in said figure. The vertical portions of said plates are provided with vertical slots f , through which are passed bolts g , which adjustably secure the shovel-standards to said plate. The shovel-standards are constructed as shown in Fig. 6, and consist of bar metal bent to form pairs of vertical standards V , connected by an integral horizontal body part, the body part 35 of the two end standards being longer than that of the two intermediate standards, and said two body parts being rigidly secured together and attached to the angular plates P , as described and shown. These standards are 40 arranged in sets of either four, as shown in Fig. 6, or three, as shown in Fig. 8, and have secured to their lower ends the shovels Z .

The slots V^3 in the body part V' , furnish means for attaching the shovel-standards to the standards of an ordinary cultivator by means of bolts or clips.

S^2 represents a pair of seat-bars having a seat-board, S' , arranged across their rear ends for supporting a seat, S , said bars being detachably connected to the cultivator-frame by means of the hook-plates n , which are secured to the inner ends of said seat-bars and hook under the braces I , and by resting on the hooks a' , which attach to the underside of axle 55 A . (See Figs. 1, 2, and 3.)

The slot T' in the tongue furnishes means for adjusting the plates J and O and F , to which the beams attach, along on the tongue to counterbalance the variable weight of an operator 60 on the seat.

When it is desired to use the cultivator as a walking-cultivator, the seat-bars S^2 and seat are removed. The bolts c and c' in slot T' of the tongue are loosened, and the plates J , O , and F , with the beams attached, are moved back to the axle A , taking the weight off the horses' necks. Handles H are then attached

to the beams, as shown in Fig. 4, by means of the brace H' and loop t , and a pin passing through the loop and handle. 70

When the cultivator is used as a riding-cultivator, the handles H are removed and placed in the loops t of the axle as a convenient place to carry them, and the beams are guided by means of the operator resting his feet on stirrups attached to the rear end of said beams, as shown at M , Fig. 7.

The rear ends of the beams B may be set and held at any required distance apart by means of tightening the bolts Q in slots Q' in plates F , so the shovels will not move to or from each other when in operation; and in such case the bolts a^2 , connecting the plates J and O , are loosened, so plate O , with the beams attached, may partially rotate, so the shovels may have side movement. When the bolts Q are loosened and bolts a^2 are tightened, the shovels may have independent side movement.

The draft mechanism is shown in Figs. 1 90 and 2, and consists of an evener, E , pivoted to the top of the tongue T ; of a pair of short secondary eveners, E' , pivoted to the axle-shanks A' by means of clips a ; of a pair of rods, R , connecting the evener E with the upper ends of the eveners E' by means of eye-bolts; of a pair of draft-rods, D , connected to the lower ends of eveners E' by means of eye-bolts and having hooks h on their outer ends for the attachment of whiffletrees, and a pair 100 of depending rods, L , suspended from the outer ends of evener E and having loops at their lower ends for receiving and supporting the draft-rods D . The evener is pivotally supported on the tongue T by means of the standard D' , secured to said tongue by means of side bolts, y , and centrally arched in its bottom part to permit the nuts or heads of bolts c , c' , and c^2 to pass under it, as shown in Fig. 5.

The pitch and angle of a set of shovels may be simultaneously adjusted by means of the slots and bolts in the angular plate P , so the rear shovels may be set to run deeper than the front shovels, or vice versa, as may be desired. 115

The shovels are formed from a plate of thin steel having the engaging end cut at an angle and sharpened to form a shear and a point at one side, and slightly curved to adapt it to 120 properly work in the soil, as shown in Fig. 9, and by means of the construction and arrangement of such a set of standards the shovels are worked in gangs, which thoroughly cuts and pulverizes the soil.

Having thus described my invention, what I claim as new, and desire to secure by Letters Patent, is as follows, to wit;

1. In a cultivator having an axle, a tongue, and a pair of traveling wheels, the combination of the shovel-standards V V' , bearing the shovels Z , angular slotted plates P , and beams B , as and for the purpose set forth. 130

2. In the cultivator shown and described,

the combination of the slotted tongue T, plate J, plate O, angular plates F F, and beams B B, as and for the purpose set forth.

3. In the cultivator shown and described, 5 the angular plates F F, having the perforations d^3 d^5 , and slots R'Q', in combination with the plate O, beams B B, and bolts c^3 and c^5 , as and for the purpose set forth.

4. In the cultivator shown and described, 10 the plate J, having the slots a^4 a^4 , and having extending perforated side legs for securing it to the slotted tongue T, and a central perforation for the reception of bolt c^2 , for pivotally connecting it with plate O, and plate O, 15 having the perforations d^3 d^3 , slots d^4 d^4 , and a central perforation for the reception of bolt c^2 , for pivotally connecting it with plate J, said plates being in combination with each other and with plates F F, beams B B, tongue T, and 20 the bolts for connecting said parts in the manner and for the purpose set forth.

5. In the cultivator shown and described, 25 the angular plates P, perforated at their rear portions so they may be pivotally attached to the cultivator-beams, and having the slots P',

f, and f, in combination with the shovel-stands V V, and beams B B, as and for the purpose set forth.

6. In the cultivator shown and described, 30 and in combination with the slotted tongue T, the plates J, O, and F, and beams B, bearing the shovels and standards, as specified, adapted to be moved horizontally on said tongue and held at any desired place within the limit of slot T' by means of the bolts c and c', substantially as and for the purpose set forth.

7. In the cultivator shown and described, 35 the combination of the beams B, having the slot c' and bolt-holes c', and angular plates F, having the perforation d', slot R', and notch 40 R', and bolts c' and c', whereby the rear ends of said beams may have vertical adjustment and be held elevated for transportation by means of bolt c' being hooked in said notch, substantially as specified.
